UNITED STATES PATENT OFFICE

ALLAN S. BARROWS, OF LOS ANGELES, CALIFORNIA, ASSIGNOR TO THE YOUNGSTOWN STEEL DOOR COMPANY, OF CLEVELAND, OHIO, A CORPORATION OF OHIO

CAR DOOR

Application filed June 27, 1924. Serial No. 722,760.

This invention relates to improvements in car doors.

One of the objects of the invention, is to provide a composite box car door including a braced metal frame of great strength and rigidity, in conjunction with closures and fillers of various materials for the said frame, according to the type of door it is desired to use.

10 Another object of the invention is to provide a braced metal door frame which is arranged for the edgewise reception of closures or fillers, together with means for removably retaining the filler in the frame, such frame being constructed so as to take care of stresses and strains upon the door in all directions and to prevent warping of the door.

Another object of the invention is to provide a frame of this character which has openings communicating with the interior space of the frame for the purpose of draining any liquid which may accumulate in such frame, and also to provide for ventilation.

Other objects and advantages of the invention will more clearly appear from the description and claims hereinafter following.

In the drawings forming a part of this specification, Figure 1 is a broken, elevational view of a car door, having portions of the same broken away to more clearly disclose the construction thereof. Figure 2 is an enlarged broken, vertical, sectional view on the line 2—2 of Figure 1. Figure 3 is a broken, enlarged, horizontal, sectional view on the line 3—3 of Figure 1. Figure 4 is a broken, front elevational view of a modified form of the invention. Figure 5 is an enlarged, broken, sectional view of the invention on the line 5—5 of Figure 4, and Figure 6 is an enlarged perspective view of a portion of the removable member used in connection with the invention.

This invention contemplates a car door of the general character disclosed in my companion application filed of even date herewith, and though broadly it includes the same general characteristics of providing a metal frame adapted for the reception of wood or other fillers, a particular adaptation of such idea will be hereinafter disclosed.

Referring to Figures 1 to 3 of the drawings, in this embodiment of the invention, the frame door includes flat side strips 10, and top and bottom strips 11 and 12, said strips being connected at their ends as by welding to provide a frame portion of rectangular formation. Secured to the side strips 10, by welding or other suitable means, are channel bars 13 and 14, having their channels disposed inwardly; and secured to the top strip 11, by rivets or other means, is a Z-bar 15, which provides a recess or groove in continuation of the channels in the bars 13 and 14. A Z-bar 16 may be removably secured to the strip 12 by means of counter-sunk bolts 171, this bar also having a recess in continuation of the channels in the side bars 13 and 14, so as to afford a continuous space or groove for the reception of the edges of a closure, so as to hold and brace the same against lateral movement, as well as endwise movement.

Diagonally disposed braces 17, preferably tubular in form, may have their ends flattened and secured to the inner flanges 18 of the channel bars 13 and 14, and to strips 11 and 12, thus bracing the frame against torsional displacement, and a cross brace 19 may extend between the channel bars 13 and 14 and be secured to the inner flanges 18 thereof. A spark strip 19' may be secured to the said channel bar 14 as shown.

A closure 20 is shown as disposed within the continuous space or guideway provided by the flanges of the channel bars and the Z-bars, and it will be appreciated that such closure is adapted for edgewise reception or removal from said space by the attachment or detachment of the Z-bar 16. Bolts 21 having their heads counter-sunk, may be extended through the channel and Z-bars and the edges of the closure as shown, for additional securing means, if desired.

The closure 20 may be, and preferably is, in the form of a standard door having the bracing strips 22 on its inner face and extending around all the four edges thereof as clearly indicated in Figures 1 and 2. It should be understood that the construction just described is not limited to wood closures, since various metal closures, not

55

60

65

70

75

80

90

95

100

shown, may be fastened to the door frame described. The closure 20 also may be in sections, or a portion of the wooden closure 20 utilized, together with a metal closure 5 for the remainder of the frame, substantially in the same manner as described in my companion application above referred to. Except as defined in the claims I do not wish to limit myself to the use of any particular 10 character of closure with the frame described, nor to a frame which slidably receives the closure throughout the length of the members, although this is an important feature of the invention. In this connection 15 it is obvious that the frame is adapted for use with a great variety of closures secured thereto in different ways.

By the arrangement just described, there is provided a metal door frame which is 20 braced against torsional and lateral strain, and is provided with an interior space to receive the edges of the filler or closure, such closure being held in the frame by means of the Z-bar 16, removal of which will permit 25 removal of the closure 20. Of course the bolts 21 are connected and disconnected during these operations, such bolts being provided as additional securing means.

Referring now to Figures 4 to 6, inclusive, 30 a unitary construction is illustrated, substantially of the same character as that before explained. In this embodiment, the frame comprises the side strips 30, and the top and bottom strips 31 and 32, respectively, as before described. T-bars 33 and 34 are secured to the side strips 30, preferably by welding, and the Z-bar 35 may be secured to the top strip 31 in the same manner, so as to provide the recess 36 at this point. A 35 Z-bar 37 may be fastened to the strip 32 by counter-sunk bolts 38, so as to be removable when desired. The Z-bar 37 provides a recess for the reception of the adjacent edges 40 of the closure, and such Z-bar preferably has openings 41, in its retaining flange 42, for the escape of water which might collect in the recess provided by such bar.

Cross brace strips 43 and 44 are provided 50 at opposite faces on the frame, preferably being secured by welding the end portions thereof to the side bars 33 and 34. Gusset plates 45 are secured at the corners of the frame, as shown, preferably by welding, so as to additionally brace the frame against 55 torsional movement.

It should be observed that the frame as 60 described is a unitary structure, and can be sold alone as an article of manufacture, it being suitable in this form for the edgewise reception of a closure member, in this case a standard wood door 46, having the usual bracing strips 47 on its inner face, such closure being shown as disposed in the frame. The strip 65 44 is preferably also secured to the member

46 by any suitable means, such as bolts or nails indicated by 144.

It should be noted with respect to the embodiment of the invention just described, that the side bars 30 are in the form of T-bars, and if desirable, I may omit the strip 44 on the outer face of the frame, so that when the Z-bar 37 is removed, the closure 46 may be disposed broad-side between the T-bars, moved beneath the Z-bar 35, and the Z-bar 37 secured in position, in this way providing for ready disposition and removal of the closure with respect to the frame, the closure being held securely in position by the Z-bars 35 and 37, and in addition bolts, not shown, may be extended through the cross brace 43, and the edges of the door in the manner before described.

It will be appreciated that I have provided a metal door frame having great strength and rigidity, in which the desired closure may be quickly and removably disposed, at the same time being firmly braced and held in the frame, resulting in a great saving of expense and affording opportunity for convenient and economical re-placement.

I have herein shown and described what I now consider the preferred manner of carrying out my invention, but the same is merely illustrative, and I contemplate all changes and modifications that come within the scope of the claims appended hereto.

I claim:

1. In a car door, the combination with a car door frame, including bracing means, said frame being arranged to provide an interior space for the edgewise reception of a closure; of a closure disposed in said space; and removable means for retaining said closure in position in such frame.

2. In a car door, the combination with a car door frame including diagonally disposed bracing means, said frame being arranged to provide an interior space for the edgewise reception of a closure; of a closure disposed in said space; and removable means for retaining said closure in position in such frame.

3. In a car door, the combination with a car door frame including bracing means at the opposite faces thereof arranged to provide an interior space for the edgewise reception of a closure; of a closure disposed in said space; and removable means for retaining said closure in position in such frame.

4. In a car door, the combination with a car door frame having braces disposed across one face thereof; of frame members providing an interior space for the edgewise reception of a closure; a closure disposed in said space; and means for retaining said closure in position in said frame members.

5. In a car door, the combination with a door frame provided with side and end members, the side members being arranged for the reception of a closure, and the end mem-

bers having recesses for accommodating the adjacent edges of said closure, one recessed member being disposed in the lowermost position with respect to said frame, and having openings communicating with the recess in said member.

6. In a car door, the combination with a door frame provided with side and end members, a pair of such members being arranged for the edgewise reception of a closure, and the other pair of members having recesses for accommodating the adjacent edges of said closure, one of said recessed members having openings communicating with the recess in said member.

10 7. In a car door, the combination with a door frame provided with side and end members, a pair of such members being arranged for the slidable reception of a closure, and the other pair of members having recesses for accommodating the adjacent edges of said closure, one of said recessed members having openings communicating with the recess in said member, and said member being 15 removably mounted.

20 8. In a car door, the combination with a door frame including channel bars disposed to provide a guideway for the edgewise reception of a closure; a closure disposed in said guideway; and members adjacent the ends of said guideway for closing the same, one of said members being removable, said members being in the form of Z-bars disposed to provide recesses; and means to which 25 said channel and Z bars are connected to maintain the same in position.

30 9. As an article of manufacture comprising a unitary door frame, including channel bars disposed to provide a guideway for the edgewise insertion of a closure, and Z-bars 40 arranged adjacent the ends of said guideway for closing the same and to provide recesses for the edges of said closure, one of said Z-bars being removable.

45 10. In a car door, the combination with channel members along two edges of the door, and Z bars along the two remaining edges of the door, said channel members and Z bars being arranged to provide recesses for the 50 reception of the edges of a filler, the flanges of said Z bars projecting outwardly beyond the portions of the door providing for the reception of the filler; and a filler spanning said frame and having its edges disposed in said recesses.

55 11. In a car door, the combination with a plurality of flat strips having their ends connected and arranged in rectangular formation; of frame members secured to a pair of 60 said strips and having means for the reception of the edges of a filler; and Z bars fixed to the remaining strips of said frame so as to provide recesses for the reception of the edges of said filler, one of said Z bars being 65 detachably connected to its related strip to

permit application and removal of said filler from said frame.

12. In a slidable door for cars and the like, the combination with a rectangular door frame comprised of bars angular in cross section, the two bars along the sides of the door frame having in-turned flanges; of closure means for the space defined by said frame, said means including a panel having bracing elements of wood on the inner face 75 of said panel along all edges thereof, the outer surface of the panel being in a single plane and lying within said in-turned flanges, one of the bars of said frame being readily removable without destructive effect whereby 80 to permit separation of the closure means from the frame.

In witness that I claim the foregoing I have hereunto subscribed my name this 5th day of June, 1924.

ALLAN S. BARROWS.
